(57) **CLAIM**

The ornamental design for a combined tottle and cap, as
shown and described.

DESCRIPTION

FIG. 1 is a front perspective view from below and one side
of the combined tottle and cap showing our new design;

FIG. 2 is a front perspective view from below with parts
separated of our new design;

FIG. 3 is a rear view of our new design;

FIG. 4 is a right side elevation of the combined tottle and
cap;

FIG. 5 is a plan view of our new design; and,

FIG. 6 is a underneath plan view of our new design.

The interior of the cap and the portions of the shoulders and
neck of the tottle that are not shown in the drawings do not
form part of the claimed design.
